UNITED STATES PATENT OFFICE.

JOSEPH MARTIN BARTOSH, OF MOUNT VERNON, IOWA.

ATTACHMENT FOR TRACTION-ENGINES.

No. 817,838.

Specification of Letters Patent.

Patented April 17, 1906.

Application filed November 26, 1904. Serial No. 234,439.

To all whom it may concern:

Be it known that I, JOSEPH MARTIN BARTOSH, a citizen of the United States, residing at Mount Vernon, in the county of Linn 5 and State of Iowa, have invented certain new and useful Improvements in Sawing Attachments for Traction-Engines, of which the following is a specification.

The object of this invention is to provide a 10 sawing device which may be easily and quickly attached to the front end of a portable engine and driven by a belt on the belt-wheel thereof.

The nature of the invention will fully appear from the description and claims following, reference being had to the accompanying drawing, which shows my improved sawing device as in use.

In the drawing, A designates the front 20 axle of a portable engine, which is usually made with lateral and vertical webs B and C and with lugs D for connection with a tongue. (Not shown.) Above this axle is the boiler E, provided with a smoke-stack F, and to the 25 boiler is attached the engine G, having a suitable driving-pulley H.

The sawing apparatus comprises a frame for the saw-arbor, a swinging carrier or cradle for the wood to be sawed, a support therefor, 30 and means for supporting the whole apparatus from the front end of the engine. These parts will now be described in detail.

The saw-frame is rectangular and is composed of side bars I and end bars J and K. It 35 is also preferably, though not necessarily, provided with a middle bar L, bolted to the end bar J on the side opposite the side bars, but in line therewith at the other end. This forms a sort of truss and makes the saw-frame very strong vertically. The cross-bar 40 K may be an angle-plate, as shown. To the cross-bar J are secured eyebolts M to connect by suitable pins or bolts with the axle-lugs D. To the frame is also secured a hook 45 N, formed of a number of converging rods extending upwardly and backwardly toward the smoke-stack F. A ring O over the smoke-stack engages the hook, and by this means the frame is firmly supported. It is to be 50 noted that the ends of the side bars I when

in position abut against the vertical web of the axle, (the end of the nearer one being broken away to show the connection with the lugs,) and this, with the suspending device and adjustable leg Y, gives a very stable support to the whole structure. 55

The saw-arbor P is mounted on the frame in the usual way by bearings Q. A pulley R takes a belt S, running over the main pulley H.

The carrier or cradle for the wood is composed of a number of bars T, pivoted on a cross-rod U, running through inclined bars V, having a trussed connection with the saw-frame by uprights V'. When a middle bar is used, it is preferably set forward of the other 65 at the rear end, so as to be out of the way of the front end of the boiler, some of which project forwardly more than the one shown. To the lower ends of the cradle-bars are attached fingers W for the wood to rest on. A spring 70 X, attached at one end to the inclined framework and at the other end to one of the cradle-bars, serves to throw the cradle back in front of the saw, as shown, to give greater safety and convenience to the operator. 75

Having thus described my invention, what I claim as new, and desire to secure by Letters Patent, is—

1. In combination with a portable engine having an axle with tongue-lugs thereon, a 80 boiler, and a smoke-stack, substantially as described, a saw-frame provided with eyebolts to engage said lugs, a suspending-hook, and a ring to encircle the smoke-stack.

2. In combination with a portable engine, 85 substantially as described, a saw-frame having inclined supports for a wood-cradle, a cradle hinged thereto at its upper end, and a spring to retract the cradle.

3. In combination with a portable engine, 90 a saw-frame composed of side bars, end cross-bars, a middle bar set at an angle to the side bars so as to truss the frame vertically when in horizontal position, diagonal supports for a wood-cradle, and a depending cradle hinged 95 to said supports.

JOSEPH MARTIN BARTOSH.
